(57) **CLAIM**

The ornamental design for a mobile mirror gym, as shown and described.

DESCRIPTION

FIG. 1 is a front, perspective view of the mobile mirror gym in an open position;

FIG. 2 is a rear, perspective view thereof;

FIG. 3 is a front view thereof;

FIG. 4 is a rear view thereof;

FIG. 5 is a left-side view thereof;

FIG. 6 is a right-side view thereof;

FIG. 7 is a top plan view thereof;

FIG. 8 is a bottom plan view thereof;

FIG. 9 is a front, perspective view of the mobile mirror gym in a closed position; and,

FIG. 10 is a rear, perspective view of the mobile mirror gym in a closed position.

The broken lines shown are included for the purpose of illustrating portions of the article which form no part of the claimed design. The arrows shown at the ends of broken lines are included for illustrating the direction of movement.
